Inventor,
Alfred G. Kilgen
By *A. G. Kilgen, R. I.*

UNITED STATES PATENT OFFICE.

ALFRED G. KILGEN, OF ST. LOUIS, MISSOURI.

ORGAN-VALVE.

1,247,844.

Specification of Letters Patent. Patented Nov. 27, 1917.

Application filed April 30, 1917. Serial No. 165,395.

To all whom it may concern:

Be it known that I, ALFRED G. KILGEN, a citizen of the United States, residing at the city of St. Louis, State of Missouri, have 5 invented a certain new and useful Improvement in Organ-Valves, of which the following is a full, clear, and exact description, such as will enable others skilled in the art to which it appertains to make and use 10 the same, reference being had to the accompanying drawings, forming part of this specification.

This invention relates broadly to pneumatic organs, and specifically to certain improvements in the valve action and valve construction for such instruments.

The object of my invention is to provide a valve construction which is very durable, in that the flexible portions are not subjected 20 to strains or creasing which tend to wear out the material; to provide a valve which is quick and certain in seating and unseating, due to the fact that it is entirely free and unattached with respect to other parts; 25 to provide a valve which is entirely noiseless in all operations; and to provide a valve and valve action which may be constructed at low cost, and repaired, if necessary, with but little trouble and expense.

30 Other and further objects will be obvious or pointed out hereinafter, reference being had to the accompanying drawings, in which

Figure 1 is a transverse vertical section through an illustrative wind chest and sound board containing my invention, and showing the valve in stopped position; and

Fig. 2 is a similar vertical section showing the valve in open or playing position.

Referring to these illustrations by the 40 reference numerals applied, let it be understood that 1 represents generally the wind chest, 2 the sound board, and 4 a pipe. The wind chest and sound board, it will be understood, are of proper dimensions to support the desired pipes, and the wind chest is arranged to be supplied with air under pressure in any suitable conventional fashion. Under each of the pipes there is formed in the bottom board of the wind chest a 45 valve chamber 5, which is adapted to be supplied with air through a channel 6, which is suitably controlled by a primary valve to govern the supply of air to the chamber 5, and its exhaust therefrom. Over 50 the chamber 5 is disposed a seating strip 7 of any suitable flexible yielding or flaccid

material, such as soft leather, and this seating strip is apertured concentrically with the chamber 5, so that an overhanging lip or ledge is left projecting inwardly from 60 the side walls of the chamber 5.

The valve is formed with a base member 8, upon which is flexibly mounted a stop head 9 of suitable soft or flaccid material, the said head being of the proper diameter 65 to close and stop the aperture in the sound board through which air is supplied to the associated pipe. To the lower surface of the base member 8 is attached a skirt 10, of comparatively light and very pliable material, such as soft leather. The skirt is of considerably greater diameter than the base member 8, so that it extends for a distance beyond and about the periphery of the latter. The diameter of the base member 8 75 is somewhat less than the diameter of the chamber 5, but greater than the diameter of the aperture in the seating strip 7. When the valve is in open position, the skirt member 10 rests flat upon the seating strip 7, 80 which latter supports the valve with the base member 8 thereon resting on the inwardly projecting or overhanging portion of the seating strip within the circumference of the chamber 5, and with the head 85 member 9 in the chamber of the wind chest and under the associated pipe opening in the sound board. A retaining piece 11 is disposed on top of the seating strip 7, and is apertured and shaped to accommodate the base 90 member 8 and the skirt 10 of the valve. The aperture in the retaining piece is adapted to receive the base member 8 loosely so as to permit its free movement upwardly and 95 downwardly between the chamber 5 and the chamber of the wind chest. At its under side the retaining piece is countersunk to provide a receiving space 11^a for the accommodation of the projecting portion of the skirt 10, and intermediate the 100 counter-sunk portion and the aperture which receives the base member 8, the retaining piece is beveled or chamfered to provide a concave or conical face, as best seen in Fig. 2. The piece 11 is suitably attached to the 105 bottom board of the wind chest, so that it will retain the valve in definite position relative to the chamber 5 and the pipe opening, and the height of the valve is such that when it is unseated and resting on the 110 seating strip 7, its head will be spaced apart from the sound board to an extent sufficient

to permit the passage of the necessary air to the pipe opening to supply the pipe, and the depth of the chamfered portion of the retaining piece 11 is such as to accommodate the skirt 10 in the movement necessary to permit the head of the valve to seat and stop the pipe opening.

In operation, pressure is maintained in the wind chest in the usual fashion, and the higher pressure of the pneumatic action is maintained in the chamber 5. This holds the valve seated to close the pipe aperture, the skirt member being forced for the most part away from the seating strip 7, and the 10 exhaust of pressure fluid from chamber 5 into the chamber of the wind chest being prevented by the close seating of the skirt 10 against the under surface of the retaining piece 11. Immediately the pressure is exhausted from chamber 5 by the operation of the primary or controlling valve, the then superior pressure in the wind chest instantly forces the valve downwardly, unseating it from over the pipe opening, and causing the blowing of the pipe. This movement of the valve is instantaneous and absolutely noiseless for the reason that the valve and its skirt have entirely free movement within the retaining piece 11, and the valve drops 20

30 noiselessly upon the overhanging and unsupported area of the flaccid seating strip 7. As soon as the superior pressure is supplied to the chamber 5, the valve will be instantly blown upwardly to close the pipe opening.

35 its entire freedom of movement making the action instantaneous and preventing any shaking or repeating. In initiating the movement to closed position, the valve is aided by the flexibility of the seat strip.

40 the unsupported portion of which is moved slightly upward by the pressure in the chamber 5, thereby increasing the effective area of pressure upon the valve, and breaking any cohesion or vacuum between the skirt member 10 and the seating strip.

45

From the foregoing, it will be seen that this construction has many advantages. As the valve is absolutely free and unattached, its movement is immediate and un retarded.

50 Due to the provision and arrangement of the skirt member 10 and seating strip 7, the seating and unseating of the valve is absolutely noiseless. In none of the movements of the valve are these flexible portions subjected to creasing, and hence their wear and durability is very great. While the valve is in closed position, the skirt member 10 is relieved of all stretching strains by virtue of the fact that it seats against the retaining

60 of the fact that it seats against the retaining member. Due to the fact that there is no sealing of the parts necessary, the cost of manufacture is greatly reduced, which also cost is also contributed to by the small amount of flexible material required. The 65 matter of repair is very simple, due to the

loose mounting of the valve, the removal of the retaining piece 11 giving full access to the valve in permitting its immediate removal and replacement.

While I have herein shown and described 70
but one embodiment, which I regard as illustra-
tive of my invention, I am aware that the
invention may be incorporated in forms dif-
ferring in various features and details from
that herein described, and it is my intention 75
that all such modifications and variations
are comprehended within the scope of the
 appended claims.

What I claim is:

- What I claim is:

  1. In a valve action, the combination of a wind chest provided with a pipe opening and a valve chamber, a seating strip of yielding material partially overlying the valve chamber, and a valve freely supported intermediate the valve chamber and the pipe opening and movable by pressure within the former into stopping association with the latter, said valve in its open position being supported by the seating strip over and within the area of the valve chamber. 90
  2. In a valve action, the combination of a wind chest having a pipe opening at one side and a valve chamber at the other, a valve freely supported within the wind chest and movable by pressure in the valve chamber to close the pipe opening, said valve having a skirt portion of flexible material arranged to close the valve chamber from the chamber of the wind chest, and valve supporting means for limiting the movement of the valve, said skirt portion being completely detached from the valve supporting means. 95
  3. In a pneumatic action, a valve structure comprising the combination of a base member formed to provide a valve chamber, a valve disposed over said chamber and having a peripheral skirt portion of flexible material extending to cover the chamber, a seating strip of yielding material disposed with a portion partially covering the valve chamber and upon which portion the valve is supported, and a retaining piece disposed to prevent movement of the valve transversely of the valve chamber and to provide a contact surface for the skirt portion spaced apart from the seating strip. 110
  4. In a pneumatic valve action, the combination of a base member shaped to form a valve chamber, a seating strip of flaccid material partially covering the valve chamber, and a valve separate from the seating strip and arranged for support thereon and having a sustaining base portion of less diameter than the valve chamber. 120
  5. In a pneumatic valve action, the combination of a base member shaped to provide a valve chamber, a seating strip of yielding material partially covering the valve chamber, a valve supported for movement onto and off of the seating strip over the 13

valve chamber, and adapted to find support on the seating strip when the valve is in open position, and means for supplying fluid pressure to the valve chamber.

5. 6. In a pneumatic valve action, the combination of a base member shaped to provide a valve chamber, a seating strip of yielding material partially covering the valve chamber, a valve supported for movement onto and off of the seating strip over the valve chamber, said valve having a skirt portion of flexible material disposed for contact with the seating strip to close the valve chamber, and means for limiting the movement of the valve away from the seating strip.

7. In a valve action, the combination of a member shaped to provide a valve chamber, a strip of yielding material disposed to partially cover the valve chamber, a retaining piece disposed over said strip, and a valve freely retained by said strip and said retaining piece, said valve having a flexible skirt portion adapted to coöperate on one side with the strip and on the other side with the retaining piece.

8. In a valve action, the combination of a movable valve having a peripheral skirt portion of flexible material, a member shaped to form a valve chamber associated with the valve, a seating strip of flexible material disposed to limit the movement of the valve toward the chamber, said seating strip being arranged for coöperation

with one side of the skirt portion, a retaining piece disposed for coöperation with the other side of the skirt portion, and means for limiting the movement of the valve away from the valve chamber; said skirt portion being movable off of and onto the said seating strip and said retaining piece.

9. In a pneumatic valve action, the combination of a member shaped to form a valve chamber, means for supplying fluid pressure to said valve chamber, a valve supported for movement by fluid pressure in said chamber, said valve including a movable portion covering the valve chamber, and means for limiting the movement of the valve relative to the valve chamber; said valve being disconnected from said means and freely movable relative to the same and to the valve chamber.

10. In a wind chest, the combination with oppositely disposed members forming walls of the wind chamber, one of which members is provided with a valve chamber, of an interposed retaining member, and a valve freely movable relative to said retaining member and retained over the valve chamber thereby, said valve having a movable skirt portion arranged to seat against the retaining member to close the valve chamber from the wind chamber.

In testimony whereof I hereunto affix my signature this 28th day of April, 1917.

ALFRED G. KILGEN.
